GEAR BOX FOR WIRE FABRIC MAKING MACHINE

Arthur E. Blashill, Worcester, Mass.

Application November 3, 1954, Serial No. 466,647

5 Claims. (Cl. 74—368)

This invention relates to improvements in a machine for manufacturing wire fabric of the chain-link type in which lengths of wire from two sources are wound into zig-zag form upon a flat rotary former bar to form a double helix of wire which is severed to length and interlaced with successively formed and fed wire helices to form the fabric as this is wound up into coil formation on the machine ready for transfer for shipment. In particular, this invention relates to improvements in the machine for manufacturing chain link fabric as disclosed in my prior U. S. Patent No. 2,202,442, issued May 28, 1940.

In my prior machine the formation of the double wire helices, the severing of the wire and the advancing of the successively interlaced helices through the machine to the wind-up shaft, including the knuckling and/or barbing of the severed ends of the helices, is controlled from a gear box which includes three laterally adjacent shafts, comprising a centrally disposed main drive shaft, actuated from an electric motor, and, on opposite sides of this shaft, a single-revolution shaft and a shaft carrying the former bar upon which the separate double helices of wire are formed and successively fed to complete the fabric.

The speed of production of the wire fabric is, inter alia, dependent upon the speed at which the wire helices can be formed on the rotary former bar and threaded into interlaced relationship with successively formed helices, together with the speed at which the advance feeding of the fabric to wind-up, and the various cut-off, knuckling and/or barbing operations can be performed.

An important object of my present invention is to provide an improved machine of the above kind with which the various manufacturing operations can be speeded up and effected in a shorter cycle compared with prior machines, including that disclosed in my said prior Patent No. 2,202,442.

Thus, it is an important object of the present invention to provide an improved machine for manufacturing wire fabric of the chain link type with which it is possible to fabricate the wire fabric quicker than is possible with existing machines, whereby the daily production of fabric under similar conditions is increased.

A further object of this invention is to provide an improved gear box which enables the former bar to be rotated at relatively high speed to form the wire fabric (a speed in the order of 600 R. P. M. being possible) and commence to rotate quickly at such speed from a slow start position.

Further objects and advantages of the invention residing in the construction, arrangement and combination of parts will appear clear from consideration of the following description with reference to the accompanying drawings and from the appended claims.

In the drawings:

Fig. 1 is a part sectional plan view of a gear box embodying the features of this invention,

Fig. 2 is a section on the line II—II of Fig. 1,

Fig. 3 is a side elevational view, and

Figure 4 is a sectional view taken on the line IV—IV of Figure 2.

Referring to the drawings, the reference numeral 10 indicates a casing structure in which there are mounted the main central drive shaft 12, the weaving spindle 14 and the single revolution shaft 16.

Shaft 12 is connected to be driven from an outside

2

motor (not shown) through a clutch (also not shown) and is rotatably mounted in the casing by bearings 18. Mounted upon the shaft 12 are a clutch 20, a large size gear 22, a small size gear 24 and a pinion 26. Clutch 20 is a friction clutch and has its inner axially adjustable part 20' keyed to the shaft 12, whereas its outer shell (indicated at 20) carries the large size gear 22 and is free to rotate, together with gear 22, relatively to the shaft. Gear 24 and pinion 26 are keyed to or rigid with the shaft.

The weaving spindle 14 is rotatably mounted in casing 10 by bearings 28 and 30, bearing 30 being conveniently provided by a "Formsprag" clutch adapted to provide a rotatable support for the spindle 14 and at the same time to prevent reverse rotation of the spindle. Mounted on spindle 14 there are a roller-cam clutch 32, gear 34, overrun clutch 36, gear 38 and worm 40. Clutch 32 is of known construction and involves an inner cam faced plate keyed to rotate with the shaft 14 and adapted to cause roller elements within the clutch casing to have wedged driving engagement between the casing and plate, or vice-versa. Dogs 42, 42' on the clutch casing are actuatable to engage and disengage the clutch 32. Gear 34 is in mesh with gear 22 and gear 38 is in mesh with gear 24.

Shaft 16 is rotatably mounted in casing 10 by bearings 44 and carries collar 46 with a radial finger 48, bevel gear 50, clutch 52 and gear 54. Collar 46 is mounted to rotate with shaft 16, as also is bevel gear 50, but clutch 52 and gear 54 are, both of which are connected as a unit, capable of being connected, as in the case of roller-cam clutch 32, to rotate with or relatively to shaft 16. Radial finger 56 on the casing of clutch 52 is operable, in a manner to be described later, to engage and disengage clutch 52.

Worm 40 on the weaving spindle 14 is in engagement with a worm wheel 58 (seen in dotted lines in Fig. 1) which worm wheel is secured upon a shaft 60 rotatably mounted upon the casing and carrying a bevel gear 62 in mesh with a bevel gear 64 on another shaft 66 upon which there is secured a chain sprocket wheel 68. A chain 70 engages said sprocket wheel and a companion sprocket wheel 72 rotatably mounted upon a pillar 74. The construction and operation of the chain 70 is substantially as disclosed in my said U. S. Patent No. 2,202,442 but in addition to having the lug 76 (equivalent to lug 32 in said patent) is also fitted with a second lug 78. Lug 78 is fitted on one side of the chain and lies in the path of the free end of arm 80 of a two-arm lever keyed to one end of a shaft 82 upon the outside of the casing 10 and having its other arm formed as a handle 84. An angularly adjustable multi-pin coupling 86 is axially slidable but keyed to shaft 66 and serves to couple the sprocket wheel 68 to shaft 66 in a desired angular relation having respect to the number of links in the chain.

Clutch 20, 20' is actuated through the medium of yoke arms 88 keyed upon the shaft 82, which shaft is mounted within the casing for oscillatory motion under the control of finger 92 on a collar 94 rigid with bevel gear 96 and actuation of the lever arm 80 by the chain lug 78.

Bevel gear 96, which is in mesh with bevel wheel 50, is secured upon a shaft 90 to which eccentrics 98 are secured for actuating bars 100 and 102 adapted to operate upon the opposite end of the fabric as this is formed, and as is disclosed in my said prior patent. Shaft 82 carries an arm 104 provided with a roller 106 with which finger 92 engages to swing shaft 82 in the direction in which yoke arms 88 are moved to positively engage clutch 20, 20'.

Referring to Figures 2 and 4, a bell crank 108 having two arms 108a and 108b is pivotally mounted by a shaft

110 in a bearing 110a within the casing 10. The arm 108b projects through a large aperture 10a in the casing and is formed with an aperture 108c which is adapted to act as a sliding bearing for a rod 112. The rod 112 extends well outside the casing and carries an adjustable collar 114 which lies within the path of the chain lug 76. At the end which lies within the casing, the rod 112 is connected for universal movement to an arm 116 of a Y-shaped lever, the pivotal axis of which is indicated at 118; the other two arms 120 and 122 of the lever operate in the manner of rocker arms. The arm 108a of the bell crank 108 is pivotally connected to one end of a bar 124 which is guided for sliding motion within the casing upon rollers 126. The bar 124 has an upstanding portion 130 adjacent the end which is connected to the bell crank and another upstanding portion 128 at the other end. The upstanding portion 128 lies in the path of finger 48, while the upstanding portion 130 forms a mounting for one end of a bolt 132 which forms a guide for a coil spring 134.

Axle 118, as seen in Fig. 3, extends to the outside of the casing and is secured to a rocker arm 136 which is on the outside of the casing and has its lower end pivotally connected with a rod 138 mounted for sliding motion upon an outside bracket 140 and spring biased by spring 142.

In Fig. 1 the gear 26 on the main drive shaft 12 is shown engaged with gear 54 on the single revolution shaft 16 through the medium of a pinion 144.

In operation and considering the machine at rest, upon main drive shaft 12 being set into motion pinion 24 will rotate gear 38, clutch 36, gear 34 and the outer casing of clutch 32. At this moment gear 22 and clutch casing 20 will also rotate idly and gear 38, acting through the clutch 36, will drive shaft 14 at a slow speed. During this time worm 40 will operate through its associated gears and shafts to set the chain 70 into motion. Upon chain lug 76 arriving at the collar 114, rod 112 will be pulled out with attendant rocking of arms 116 and 122 to move the outer end of arm 122 into the path of dog 42' as shown in Fig. 1. At the same time the free end of arm 120 is rocked out of the path of finger 56. This causes clutch 32 to be arrested against rotation and positively stops weaving spindle 14 in a set predetermined position. With clutch 32 temporarily held against rotation, gear 26 through pinion 144 rotates gear 54, which in turn rotates clutch 52 together with the single revolution shaft 16, and bevel gears 50 and 96. During one revolution of shaft 16 finger 92 hits against roller 106 to rock lever arm 104 and hence shaft 82, the effect of which is to cause yoke arms 88 to move and positively engage clutch 20, 20'. When this occurs gear 22 positively drives onto gear 34 with a high gear ratio and overruns the still rotating clutch 36 to thereby take over the rotation of the weaving spindle through clutch 32 at high speed. With the spindle operating at high speed, continued movement of the chain 70 will bring lug 78 against the end of arm 80 to thereby rock shaft 82 in the opposite direction and positively disengage the high speed clutch 20, 20'. Rotation of weaving spindle 14 will then proceed at slow speed through the low ratio gears 24, 38 and the clutch 36, which is now not in a condition of overrun. When shaft 16 approaches the end of one complete revolution finger 48 will hit against projection 128 on bar 124 and push this bar to the right, as seen in Fig. 2, against the action of spring 132. This movement of bar 124 rocks bell-crank 108 to release the collar 114 on rod 112 from the path of chain lug 76. This movement of the bell-crank is attendant with movement of arm 120 into the path of finger 56 on the clutch 52 of the one revolution shaft at the same time as arm 122 is moved out of the path of dog 42', thereby permitting the spindle 14 to recommence rotation at slow speed. After finger 48 has acted against bar 28 but before finger 56 contacts the raised arm 120 the single

revolution shaft 16, through bevel gears 50 and 96, will bring finger 92 into action to rock arm 104 and shaft 82 into position in which clutch 20, 20' is again positively engaged for high speed rotation of spindle 14.

5 I claim:

1. A wire fabric machine comprising a main drive shaft, a weaving spindle, an overrunning clutch having a driven and a driving element, the driven element being connected to the spindle, a low-speed transmission connecting the shaft to the driving element of the clutch, a high-speed transmission connecting the shaft to the driven element of the clutch, the high-speed transmission and the low speed transmission being connected to the spindle through a roller-cam clutch, and means for causing the high-speed transmission to transmit power after the weaving spindle has been driven by the low-speed transmission for a predetermined period of time.

2. A wire fabric machine comprising a main drive shaft, a weaving spindle, an overrunning clutch having

20 a driven and a driving element, a low-speed transmission connecting the shaft to the driving element of the clutch, a high-speed transmission connecting the shaft to the driven element of the clutch, a roller-cam clutch connecting the driving element of the overrunning clutch to the spindle, and control apparatus driven by the spindle for causing the high-speed transmission to transmit power after the weaving spindle has been driven by the low-speed transmission for a predetermined number of revolutions.

30 3. A wire fabric machine comprising a main drive shaft, a weaving spindle, an overrunning clutch having a driven and a driving element, a low-speed transmission connecting the shaft to the driving element of the clutch, a high-speed transmission connecting the shaft to the driven element of the clutch, the high-speed transmission including a friction clutch, a roller-cam clutch connecting the driven element of the overrunning clutch to the spindle, and means for causing the friction clutch to transmit power after the weaving spindle has been driven by the low-speed transmission for a predetermined period of time.

4. A wire fabric machine comprising a main drive shaft, a weaving spindle, a unidirectional clutch connected to the spindle, an overrunning clutch having a driven and a driving element, the driven element being connected to the unidirectional clutch, a low-speed transmission connecting the shaft directly to the driving element of the overrunning clutch, a high-speed transmission connecting the shaft to the driven element of the overrunning clutch, the high-speed transmission including a friction clutch, the unidirectional clutch connecting the driven element of the overrunning clutch to the spindle, and means for causing the friction clutch to transmit power after the weaving spindle has been driven by the low-speed transmission for a predetermined period of time.

5. A wire fabric machine comprising a main drive shaft, a weaving spindle, a sensitive unidirectional clutch connected to the spindle, an overrunning clutch having a driven and a driving element, the driven element being connected to the unidirectional clutch, a low-speed transmission connecting the shaft directly to the driving element of the overrunning clutch, a high-speed transmission connecting the shaft to the driven element of the overrunning clutch, the high-speed transmission including a friction clutch, and control apparatus driven by the spindle for causing the friction clutch to transmit power after the weaving spindle has been driven by the low-speed transmission for a predetermined number of revolutions.
